UNITED STATES PATENT OFFICE.

HERMANN J. GIES, OF PETERBOROUGH, NEW HAMPSHIRE.

COMBINED FOLDING BATH AND WASH TUB.

SPECIFICATION forming part of Letters Patent No. 592,701, dated October 26, 1897.

Application filed January 12, 1897. Serial No. 618,965. (No model.)

To all whom it may concern:

Be it known that I, HERMANN JOSEPH GIES, of Peterborough, in the county of Hillsborough and State of New Hampshire, have invented 5 a new and Improved Combined Folding Bath and Wash Tub, of which the following is a full, clear, and exact description.

The object of the invention is to provide a new and improved combined folding bath 10 and wash tub which is simple and durable in construction and arranged to take up little space when folded and not in use and to permit of readily converting the bath-tub into a washtub when desired.

15 The invention consists of certain parts and details and combinations of the same, as hereinafter more fully described, and pointed out in the claims.

Reference is to be had to the accompanying 20 drawings, forming a part of this specification, in which similar characters of reference indicate corresponding parts.

Figure 1 is a sectional side elevation of the improvement in an extended position. Fig. 25 2 is a sectional plan view of the same with the tub in a folded position. Fig. 3 is a perspective view of the folded-up tub ready to be moved about. Fig. 4 is a sectional plan view of the water-supply back, and Fig. 5 is 30 an enlarged transverse section of the locking device for the partition in the tub.

The improved tub is provided with a suitably-constructed base A, provided with casters A' and with standards A', in which are 35 journaled the pivots B and B', held in the sides of the bath-tub casing C, containing the usual tub D, of sheet metal or other material. The pivots B and B' are located a suitable distance from the head of the bath-tub and 40 near the under side thereof, as plainly indicated in Fig. 1, to permit of swinging the bath-tub, with its casing, either into a vertical position, as indicated in dotted lines in Fig. 1 and in full lines in Fig. 3, or to swing the 45 said bath-tub into a horizontal position, as shown in Fig. 1, the outer end of the tub then being supported on suitable legs C', pivoted to the sides of the casing C. When the bath-tub is in this position, it can be used in the 50 usual manner for taking a bath. When it is desired to convert the tub into a washtub, then I insert into the tub D a transverse par-

tition E, so as to divide the tub into the two compartments D' and D'', either of which can be used as a washtub. The transverse partition E is formed at its lower edge to the shape of the bath-tub and is provided thereon with a packing E' of rubber, felt, or other material and adapted to engage a correspondingly-shaped packing D'', secured to the inner 60 surface of the tub D.

In order to securely hold the transverse partition in place in the tub D, I provide the sides thereof with cleats or guideways F, and the top of the partition is pressed on by cam-levers G engaging with their cam-surfaces G' the corresponding bearings E'', secured to the top of the partition E. The trunnions G'' of the cam-levers G engage forked and curved arms D'', secured to the sides of the 70 casing C, as plainly shown in Figs. 1 and 5, so that the cam-levers can be readily removed when the partition is not to be used. Now it is evident that when the partition E is set in the guideways F and the cam-levers G are 75 swung inward and downward into the position shown in Fig. 5 then the cam-surfaces G' press the bearings E'', so as to force the partition E downward to firmly engage the packing E' with the packing D'' to form a 80 very tight joint between the partition and the tub. Thus the water contained in either of the compartments D' or D'' cannot leak from one to the other. In the bottom of the tub D are arranged two outlet-pipes H and 85 H', extending into the compartments D' and D'', so as to drain either of the latter whenever desired by removing the usual plug set in the opening of the corresponding pipes H and H'. The two pipes H and H' connect with the 90 pivot B, preferably made in the shape of a pipe and formed at one end with an outlet-faucet B'', by means of which the water of the tub may be drawn off into a pail when the tub is not stationary, and provided at its other 95 end with a coupling H'', connecting with the discharge-pipe H'', adapted to be connected with the soil-pipe to carry the water to a sewer or other place when the tub is stationary. The connection between the pipe H'' and the 100 pipe B is in the form of a coupling to permit the pipe H'' to remain stationary while the casing, with the bath-tub D, is swung into a vertical position or back into a horizontal

position. The pipes H and H' extend to the under side of the casing C, and in order to give ready access to the said pipes and the coupling H, I provide the bottom of the casing C with a hinged door C², adapted to be seated with its beveled edge on the corresponding upper end A³ on the cross-bar A⁴, forming part of the base A. A spring C³ presses on the door C², so as to hold the latter normally closed when the casing C and the tub D are in a folded vertical position.

When the tub and casing are swung downward, then the beveled edge of the door C² glides down over the beveled edge A³ of the cross-bar A⁴, so that the door opens automatically. (See Fig. 1.)

When the bath-tub is used in connection with the regular city water-supply, then a water-back I is provided secured in the usual manner to the wall of the bath-room and provided with suitable faucets J, adapted to discharge the water into a trough K, pivoted at K' to the top of the table L, fulcrumed at its sides at L' to the sides I' of the water-back I. The forward end of the trough K extends over the head of the bath-tub, so as to discharge the water into the latter at the compartment D'. The free end of the table L is provided at its sides with friction-rollers at L², traveling on the side-rails of the casing C, so that when the latter is swung upward the said table swings in a like direction and falls against the back I, as indicated in dotted lines in Fig. 1. A spring L³ presses against the table L, so that when the casing C is swung outward the said table L moves in a like direction with the friction-rollers L², traveling on the rails of the casing C. Now it is evident that by the arrangement described the bath-tub can be readily swung into a folded position, so as to take up very little space in the bath-room, and it can be readily swung into a horizontal position and filled with water for taking a bath, or it can be divided into two compartments by the insertion of the partition E, so as to permit of using one of the compartments as a washtub. The water from either compartment can be drained at any time by removing the usual plugs from the pipe H and H'. If desired, the tub D, with its casing C and base A, can be readily moved from one room to another whenever desired, the casing then being in a folded position on the top of the base A, as indicated in dotted lines in Fig. 1, so as to allow of conveniently wheeling the base A over the floor from one room to another. The outer com-

partment of the tub can be filled by a hose leading from the faucet J, or the tub can be filled before the partition is put in place.

Having thus described my invention, I claim as new and desire to secure by Letters Patent—

1. A combined folding bath and wash tub, comprising a base, a casing pivoted to the base a short distance from one end, one of the pivots being tubular, a tub in the casing, a removable partition in the tub and dividing the same into two compartments, and a pipe leading from the bottom of each compartment to the tubular pivot, substantially as described. 70

2. A combined folding bath and wash tub, comprising a base, a casing containing a tub and having a chamber below the tub, said casing being pivoted to the base a short distance from its end, one of the pivots being tubular, a removable partition in the tub and dividing the same into two compartments, and a pipe leading from each compartment to the tubular pivot, one of said pipes being in the chamber of the casing, substantially as described. 75

3. A combined folding bath and wash tub, comprising a base having standards at its front end, a casing containing a tub and having a chamber below the tub, said casing being pivoted to the standards a short distance from its end, one of the pivots being hollow, a removable partition in the tub and dividing it into compartments, a pipe leading from each compartment to the tubular pivot, one of the pipes being in the chamber of the casing, and a spring-pressed door hinged to the bottom of the tub at its pivoted end, substantially as herein shown and described. 80

4. The combination with a pivoted bath-tub and a water-back having faucets, a table pivoted on the said water-back and adapted to ride with its free end on the side rails of the said tub, and a trough pivoted on the table and adapted to carry water from the said faucet to the said bath-tub, substantially as shown 90 and described. 95

5. The combination with a base, of a bath-tub casing pivoted on the said base and provided with a spring-pressed door, having its lower edge beveled to engage a correspondingly-beveled edge on a cross-bar of the said base, substantially as shown and described. 105
